UNITED STATES PATENT OFFICE

JOSE LEANDRO MONTALVO GUENARD, OF PONCE, PORTO RICO

TENNIS RACKET

Application filed November 7, 1929. Serial No. 405,441.

This invention relates to tennis rackets. It is among the objects of the present invention to provide a novel and improved tennis racket in which separable members are provided for securing within the racket frame the usual racket mesh.

A further object of the present invention is to provide a tennis racket the frame of which includes a hinged portion adapted to removably secure a racket mesh in the frame.

A further object of the present invention is to provide a tennis racket including a handle and integrally formed mesh frame together with a hinged member secured to said frame for engagement with said frame to secure the mesh therebetween.

Another object of the present invention is to provide in a tennis racket having a hinged mesh-securing member, a novel securing means for securing the frame and hinged member in mesh-engaging position.

Other objects of the present invention include the combination and interrelation of parts whereby a novel, simple and improved tennis racket is provided which is economical in manufacture and in which the mesh may be readily changed.

Further objects of the present invention will be apparent from a consideration of the following specification taken in conjunction with the accompanying drawings, in which

Figure 1 is a front elevation of one form of the present invention;

Fig. 2 is a sectional view taken on the lines 2-2 of Fig. 1;

Fig. 3 is a sectional view taken on the lines 3-3 of Fig. 1;

Fig. 4 is a plan view of the racket opened;

Fig. 5 is a detail view of the retaining ring;

Fig. 6 illustrates a preferred form of clamp adapted for use in connection with the present invention.

Referring more particularly to the drawings, the racket of the present invention includes a handle portion 10, of conventional configuration, from which extends a frame section 11, which is preferably formed integral therewith and which is grooved on its inner face as at 12. In considering the present invention it will be understood that

the invention is not confined to any specific type of handle nor to the specific handle and frame section herein illustrated, as the frame section 11 may be formed separately from the handle 10 and secured thereto in any desired manner.

Associated with the handle portion 10, there is provided a complementary frame section 13, provided with an annular projection or ridge 14 which is adapted for co-operation with the groove 12 as will be hereinafter explained. The section 13 is hingedly secured to the handle 10 by the provision of a hinge member 15, which preferably extends downwardly from the pivotal point to provide an extending reinforcing plate 16, as shown in the drawings. The opposite side of the handle 10 is also provided with a reinforcing plate 17, which in conjunction with the plate 16, provides for reinforcement of the racket at the juncture of the handle and frame.

The racket further includes the conventional mesh 18, the edges of which are preferably secured between rubber tissue sheets 19 or equivalent resilient members which are adapted to firmly secure the peripheral edges of the mesh.

For securing the mesh in the frame of the racket, the section 13 is brought to the full-line position shown in Fig. 2, by which the ridge 14 co-operates with the groove 12 in securely locking the mesh in stretched position as indicated in Fig. 2. For securing the sections 11 and 13 in mesh-engaging position as shown in said figure, a peripherally extending securing ring 20 is provided which is substantially U-shape in cross section and includes a central wall which engages the periphery of both the sections 11 and 13, together with the depending side walls which engage the beveled outer edges of the sections 11 and 13, the arrangement being such that when the ring 20 is in position, the sections 11 and 13 are locked securely in position whereby the ridge 14 and groove 12 co-operate to secure the mesh 18 in position. For securing the ring 20 in the engaging position shown in Figs. 1 and 2, a securing assembly illustrated in Fig. 3, is provided, which assembly includes an internally threaded shaft 21 ex-

tending diametrically across the handle 10 and including a head 22 which engages one of the ends of the ring 20. The other end of the ring is secured by an externally threaded 5 bolt 23 which is receivable within the shaft 21 for threaded engagement therewith, the head 24 of the bolt 23 engaging the outer surface of the opposite end of the ring 20. The ring 20 of the present invention together with the 10 plates 16 and 17, is preferably formed of aluminum or similar light, durable material, the arrangement being such that the normal balance is maintained and no departure from the average weight of standard rackets will 15 be experienced.

In connection with the present invention, it will readily be seen that should the mesh of the racket be ruptured, a loosening of the bolt 23 will permit the ring 20 to be removed 20 and the securing element 13 may be moved to the dotted line position as shown in Fig. 2, which permits the mesh 18 to be removed and a suitable pre-formed mesh may be inserted in lieu thereof. After such insertion, the element 25 13 is moved to its normal position and secured to engage the new mesh by the securing ring 20. It will be seen that the handle 10 is reinforced at its weakest point by the provision of the plates 16 and 17.

30 In connection with the present invention it will readily be seen that the device is adapted for use with various types and modifications of woven mesh or with a pre-formed perforated mesh-resembling sheet. In the 35 provision of an inexpensive or toy racket, it will be understood that the mesh may be formed of cane or other material less expensive than the usual mesh provided for professional rackets. In the use of mesh for the racket, it will be seen that the present invention 40 provides for the use of a pre-formed mesh which may be secured already woven ready for cutting and insertion in the racket.

Referring particularly to Fig. 6 of the 45 drawings, it will be seen that a clamp is provided for insuring a proper assembly of the mesh with the racket. The clamp includes a base plate 30, the edge of which is grooved as at 31 and co-operates with an upper plate 50 32 having a grooved edge 33. The upper plate is movable by a suitable screw 34, so that when the mesh is laid upon the frame, the frame may be positioned between the plates 30 and 32, and operation of the screw 55 will force the movable frame into proper position for associating the ridge 14 with the groove 12, whereby the retaining ring 20 may be positioned for securing the parts in proper operative connection.

60 From the foregoing it will be seen that the invention provides a novel and improved racket, in which the mesh may be readily replaced without loss of time and without requiring a skilled racket stringer.

65 It will be understood that the invention is

not confined to the specific structural details herein illustrated, but that numerous changes, modifications and the full use of equivalents may be resorted to without departing from the spirit or scope of the invention as outlined in the appended claims. 70

What is claimed is:

1. A tennis racket, including a handle and an associated frame section, together with a pivoted mesh-securing member adapted for 75 co-operation with said frame to engage a mesh therebetween.

2. A tennis racket, including a handle and an associated frame section, together with a pivoted mesh-securing member adapted for 80 co-operation with said frame to engage a mesh therebetween, said frame including an annularly extending groove adapted to receive said mesh and secure it in taut position.

3. A tennis racket, including a handle and an associated frame section, together with a pivoted mesh-securing member adapted for 85 co-operation with said frame to engage a mesh therebetween, said frame including an annularly extending groove adapted to receive said mesh and secure it in taut position, said securing member including a ridge adapted to co-operate with said groove in retaining said mesh. 90

4. A tennis racket, including a handle and an associated frame section, together with a pivoted mesh-securing member adapted for 95 co-operation with said frame to engage a mesh therebetween, said frame including an annularly extending groove adapted to receive said mesh and secure it in taut position, said securing member including a ridge adapted to co-operate with said groove in retaining said mesh, and a retaining ring receivable over the periphery of said frame for 100 locking said frame and securing member in mesh-engaging position. 105

5. In a tennis racket, a handle, a frame on said handle, and a securing element hingedly connected with said handle for co-operation 110 with said frame.

6. In a tennis racket, a handle, a frame on said handle, a securing element hingedly connected with said handle for co-operation with said frame, and mesh secured to said 115 frame by said securing element.

7. In a tennis racket, a handle, a frame on said handle, a securing element hingedly connected with said handle for co-operation with said frame, and mesh secured to said frame by said securing element, said element conforming in configuration to the configuration of said frame. 120

8. In a tennis racket, a handle, a frame on said handle, a securing element hingedly connected with said handle for co-operation with said frame, and mesh secured to said frame by said securing element, said element conforming in configuration to the configuration of said frame and including a ridge 125 130.

adapted for co-operation with a groove in said frame for securing said mesh therebetween.

9. In a tennis racket, a handle, a frame on said handle, a securing element hingedly connected with said handle for co-operation with said frame, mesh secured to said frame by said securing element, said element conforming in configuration to the configuration of said frame and including a ridge adapted for co-operation with a groove in said frame for securing said mesh therebetween, and resilient sheets carried on each side of said mesh for assisting said frame and element to secure said mesh.

10. In a tennis racket, a handle, a frame on said handle, a securing element hingedly connected with said handle for co-operation with said frame, mesh secured to said frame by said securing element, said element conforming in configuration to the configuration of said frame and including a ridge adapted for co-operation with a groove in said frame for securing said mesh therebetween, resilient sheets carried by each side of said mesh for assisting said frame and element to secure said mesh, and a retaining ring receivable over the peripheries of said frame and element for securing them in mesh-engaging position.

11. In a tennis racket, a handle, a frame on said handle, a securing element hingedly connected with said handle for co-operation with said frame, mesh secured to said frame by said securing element, said element conforming in configuration to the configuration of said frame and including a ridge adapted for co-operation with a groove in said frame for securing said mesh therebetween, resilient sheets carried on each side of said mesh for assisting said frame and element to secure said mesh, a retaining ring receivable over the peripheries of said frame and element for securing them in mesh-engaging position, and threaded means for securing said retaining ring.

JOSÉ LEANDRO MONTALVO GUENARD.
